(57) **CLAIM**

The ornamental design for an automobile tire tread, as shown and described.

DESCRIPTION

FIG. 1 is a front view of an automobile tire tread showing the new design;

FIG. 2 is a rear view thereof;

FIG. 3 is a left side view thereof;

FIG. 4 is a right side view thereof;

FIG. 5 is a perspective view thereof; and,

FIG. 6 is an enlargement of a portion of the front view. The broken line depictions of tire sidewalls are illustrative of environmental structure and form no part of the claimed design.
